SELF-OPENING AND CLOSING MOUTHPIECE
FOR COLLAPSIBLE TUBESDaniel D. Devlin and Reinhart W. Pittman,
New York, N. Y.

Application February 28, 1931. Serial No. 518,974

9 Claims. (Cl. 221—60)

This invention relates to means for conveniently and thoroughly extruding the contents from collapsible tubes through a self-opening and closing mouthpiece by applying pressure to the exterior of the tube in the usual manner, or by providing a binder such as is now employed to seal the tube end, but to provide this binder with an extension to form a finger piece by means of which the tube can be rolled up on the binder to force the contents forward to the mouthpiece, or additional means may be used with the present binder to serve as a finger grip to connect with the binder to rotate the same to roll the tube thereon.

It is one object of the invention to provide a simple construction of the mouthpiece that can be produced at a low cost, that the same may be supplied with the tube, instead of the screw cap now used to close the tube outlet.

Another object is to provide the binder that seals the other end of the tube with a separate means to engage the binder and having a finger grip by means of which the binder may be rotated and roll up the tube to force the contents forward in the tube to extrude it from the self-opening mouthpiece, or the binder itself may have an extension to provide a finger grip and be supplied with the tube.

A further object is to arrange these members in such a manner that one hand will suffice to discharge the contents from the tube whereby the other hand is free to hold an article to which contents may be applied.

In the use of collapsible tubes the general practice is to unscrew the cap and lay it aside, then pick up the tooth brush or other article to which the application from the tube is to be made by squeezing the tube, thus requiring the use of both hands. With the self-opening mouthpiece, however, this operation is much simplified, since the tube has only to be squeezed in the usual manner, or by providing a convenient means to progressively force the contents forward and drain the tube systematically and thoroughly by this forward action forcing the desired quantity from the self-opening mouthpiece onto the article, and on the release of the pressure the mouthpiece will automatically close.

Other objects will appear and be more fully pointed out and described in the drawing forming a part of this specification, in which like characters designate corresponding parts in the several figures of which:

Figure 1 is a perspective view of a collapsible tube provided with this improved self-opening and

closing mouthpiece and the usual binder to seal the other end of the tube.

Fig. 2 is a plan view of a tube with this improved mouthpiece to more clearly show the construction and further shows a binder provided with an extension by means of which the tube may be rolled up on the binder to force the contents forward in the tube.

Figs. 3 to 7, inclusive, show in detail the self-opening and closing mouthpiece.

Fig. 8 is a view of the binder for sealing the tube provided with an extension forming a wing grip portion by means of which the tube may be rolled up.

Fig. 9 is a similar view but showing the binder with the tube partly rolled up on the binder.

Fig. 10 is a view of another form of the means for pressing the contents of the tube to extrude same from the mouthpiece.

Fig. 11 is a detail of another form of the rolling up means.

Fig. 12 is a modification showing a simple form of the rolling up means.

As shown, the usual tube 2 provided with the threaded end 3 adapted to receive the closure cap 80 that is generally supplied with the tube, is utilized to receive the threaded bore 4 of a self-opening and closing mouthpiece 5 that serves as a closure cap at all times except when desired to extrude some of the contents from the tube by pressing 85 or squeezing the tube without removing this closure from the tube.

We do not wish to limit our invention to any particular form of attachment of the mouthpiece to the tube since it may be integral with this 90 tube, or attached in any other manner.

The principal feature of our invention is to provide a self opening and closing mouthpiece controlled by the application of pressure which may be obtained in any desirable manner, such as 95 directly squeezing the tube as is usually done, or by means, as will be shown, by rolling up the tube by providing a wing grip to the binder indicated at 6 that permanently seals the end 7 of the tube, whereby the binder may be rotated by this grip 100 and the binder part will act as a core to roll up the tube thereon. By providing this wing grip in connection with the self-opening and closing mouthpiece we are enabled to extrude any desired quantity from the tube by the use of one hand only leaving the other hand free to hold an article to which it is desired to apply the contents from the tube. Usually tubes, when subjected to direct squeezing, are not entirely drained due to careless handling. By rolling up, the tube as just de- 110

scribed moves the contents progressively forward in the tube as it is used and when the tube becomes shorter by this action the rolling up becomes more effective and convenient for manipulation 5 by the one hand as will be readily understood. In the use of the screw cap generally supplied with such tubes, it is the general practice to remove and replace the cap before and after use. This plan is hardly ever carried out, the cap being mislaid or 10 forgotten and the tube is left in an unsanitary condition and the material dried at the discharge opening. Our invention obviates these conditions by supplying a substitute for the cap that delivers its contents through a self-closing spring 15 pressure plate that fits snugly between side walls of the mouthpiece but free enough between the walls to respond to pressure from within the tube to open the spring plate, and self-closing, when the pressure ceases.

20 We prefer to construct this mouthpiece by forming the body 10 of mouldable material and shaped to form an extended runway 11 preferably rectangular and open at the top forward end, the greater part of its extended length and 25 this open top terminating a short distance from the front of the head 12 at which place a top wall 13 provides a shelf-like arrangement, having recesses 14—14 at each side formed in the side walls 15 which, at this location, extend upward over 30 the shelf. The top of the shelf has a depression 16 located at the center of the shelf to hold the spring plate 17 which is of a uniform width and has an outer bend 18 so bent with relation to the forward end 19 that a predetermined pressure 35 is effected on the front face 11' when the bent end of the spring 18 is pushed into the recesses 14 and thereby provide a yieldable closure between the end of the spring plate 17' and the front of the mouthpiece at this front face 11'. The depression 16 in the shelf 13 serves as a lock shoulder against a yielding tongue portion 18' that locks behind the shoulder 18'' of the depression 16 when this spring plate is forced fully back and into the recesses 14 as clearly shown in Fig. 3.

40 The head 12 of the mouthpiece, which may be of any desired form, that is, round, hexagonal or knurled or otherwise arranged for a comfortable finger grip so it may be readily unscrewed from the threaded part 3 of the tube if desired; but it 45 is understood, however, that the mouthpiece may be an integral part of the tube or fitted in any other manner to provide a removable separate part. In Fig. 10 is shown a separate means for rolling up the tube, the usual binder 20 for closing the tube being retained and a tubular member 21 provided with a slot 22 of such proportions to freely admit the binder 20 therein and by rolling the tube forward, the contents may be 50 thoroughly and conveniently extruded through the yielding mouthpiece by a one hand operation as indicated in this figure by broken lines. The tubular member 21, may be formed as in Fig. 11 by bending the member into tubular form and leaving an open joint 24 with rounded edges, so 55 the binder of the tube may be pressed into the joint 24 from the side, the tube acting as a spring to grip and hold the binder. In Fig. 12 a modified form of the rolling up member is shown, wherein a slotted bar 30 is fixed to a circular grip portion 31, and the binder is slipped into the slot 32 and the head rotated to wind up the tube.

60 From the foregoing it will be obvious that with the self-opening and closing mouthpiece one hand only is required to squeeze the tube and eject from the mouthpiece the quantity desired and apply it

directly to the article held by the other hand, providing by this means a much simplified operation which also saves considerable time over the method now employed.

While direct squeezing of the tube to extrude the contents cannot always be relied upon to thoroughly and fully remove the contents, the rolling up of the tube on the binder by providing a convenient form of finger grip systematically moves the contents forward in the tube and such a grip provides more power, thereby making the operation much easier and reliable for forcing out a given quantity without overriding.

What we claim is:—

1. A collapsible tube comprising a flexible tube member, having at one end a head to receive a spring controlled mouthpiece and a binder to close the other end, said mouthpiece including a body portion adapted to be removably attached to the tube, a passage in the body having communication with the interior of the tube, a channel portion extending forward of the body and being a continuation of the passage, and a leaf spring fixed within the body and extending forward in the channel to lie between the side walls 100 thereof and form a cover to close the passage and channel outlet. 90

2. A discharge head for a collapsible tube, comprising a head with a tubular extension that has a projecting bottom wall, an upright wall on each side of said bottom wall with the extension above said bottom being left open, and a plate spring secured to the top of the extension at the rear of the open top which spring extends downward between the side walls into contact with the bottom wall at its outer end portion to close the passage through the extension normally but which will yield upwardly on extruding pressure in the tube, and which plate spring is exposed on its upper face for removal of the substance 110 that has been extruded. 105

3. A discharge head for a collapsible tube, comprising a head with a tubular extension that has a projecting bottom wall, an upright wall on each side of said bottom wall with the extension 120 above said bottom being left open, and a plate spring secured to the top of the extension at the rear of the open top which spring extends downward between the side walls into contact with the bottom wall at its outer end portion to close the passage through the extension normally but which will yield upwardly on extruding pressure in the tube, and which plate spring is exposed on its upper face for removal of the substance 125 that has been extruded, said side walls having the upper edges inclined downwardly to the outer end to lie normally a short distance above the said inclined spring plate. 130

4. A discharge head for a collapsible tube, comprising a head with a tubular extension that 135 has a projecting bottom wall, an upright wall on each side of the bottom wall with the extension above said bottom being left open, and a plate spring secured to the top of the extension at the rear of the open top which spring 140 extends downward between the side walls into contact with the bottom wall at its outer end portion to close the passage through the extension normally but which will yield upwardly on extruding pressure in the tube, the rear top wall of the extension being provided with an overhanging flange on each side to engage and secure said spring plate. 145

5. A discharge head for a collapsible tube, comprising a head with a tubular extension that

- has a projecting bottom wall, an upright wall on each side of the bottom wall with the extension above said bottom being left open, and a plate spring secured to the top of the extension at the 5 rear of the open top which spring extends downwards between the side walls into contact with the bottom wall at its outer end portion to close the passage through the extension normally but which will yield upwardly on extruding pressure 10 in the tube, the rear top wall of the extension being provided with an overhanging flange on each side to engage said spring plate, said top wall having an opening, and the spring plate having an ear engaging said opening to retain 15 the plate in position. 6. A container closure comprising a cap having a bore therein for the passage of the container contents and further having a chamber extending thereinto from one side thereof and 20 communicating with the bore for receiving the container contents therefrom, a resilient valve operable in the chamber for controlling the discharge of the container contents, and means on the cap at the inner end of the chamber for 25 rigidly clamping one end portion of the resilient valve to the cap. 7. In a collapsible tube, a head on the end of the tube, a nozzle connected to the head having a bore, a channel forming an opening at one side 30 of the bore, said channel having parallel sides and a connecting flat base, the edge of the base and the sides of the channel forming a discharge orifice, a single valve closure in the form of a 35 leaf spring secured to the side of the nozzle at the end of the channel, the spring fitting in the channel and engaging said flat base at the end of the nozzle, said spring releasing to form an opening on internal pressure of the material in the tube and retracting to form a closure on release of such pressure. 8. A paste dispenser for collapsible tubes comprising a nozzle having a bore and a channel forming an opening at one side of the bore, the channel having parallel sides, and a portion of the bore forming a base of the channel, a valve in the form of a leaf spring secured at one side of the nozzle at the end of the channel, said spring having an operating fit between the sides of the channel, and the end of the spring engaging the opposite side of the nozzle adjacent its outer end, the spring being moved to form an opening by an internal pressure of material in said bore, and retracting to form a closure on release of such pressure. 9. A container consisting of a collapsible tube provided with a neck at its delivery end, a spout extending therefrom in alignment therewith and having its back and opposite sides closed and its 100 front open, and a sealing spring forming a closure for the open front of the spout and extending longitudinally therefrom between the sides thereof and arranged to abut the back of the spout whereby the spout will be sealed. 105
